UNITED STATES PATENT OFFICE.

MELVIN EDGAR MERKER, OF NEW YORK, N. Y.

TOOTH.

1,109,080.

Specification of Letters Patent.

Patented Sept. 1, 1914.

Application filed November 22, 1911. Serial No. 661,682.

To all whom it may concern:

Be it known that I, MELVIN E. MERKER, a resident of New York, in the county and State of New York, have invented certain new and useful Improvements in Teeth; and I do hereby declare the following to be a full, clear, and exact description of the invention, such as will enable others skilled in the art to which it pertains to make and use 10 the same.

This invention relates to artificial teeth, the main object being to provide an improved tooth of the character indicated, and improved means for securing the same in a 15 user's mouth.

The invention consists in the construction hereinafter described and particularly pointed out in the claims.

In the accompanying drawing which illustrates the invention and forms part of the specification,—Figure 1 is a longitudinal section of a tooth and securing means on a natural root; Fig. 2 shows a side and plan view of the securing device; Fig. 3 is a view 25 looking at the base of the tooth; Fig. 4 is a side view showing a modification of the securing device; Fig. 5 is a longitudinal section showing another securing means; Fig. 6 shows a vertical section and a plan of a 30 molar or a back tooth with the improvement embodied therein.

The incisor or front artificial tooth 1 comprises in its base a plurality of holes 2 formed therein in any suitable manner, preferably by boring. These holes are situated in or near a common plane passing through the front and back of the tooth, as distinguished from a plane passing through the side edges of the tooth. Said holes are 35 adapted and designed to receive securing pins 3 after the tooth is baked, the pins being then cemented in the holes, whereby said pins, which may be of platinum or platinum filled or any suitable metal and are quite 40 small, are not subjected to high heat.

The pins 3 are connected by an integral cross piece 4 to which is secured the pin 5 designed to enter a prepared root, as shown. The pin 5 is in all cases situated centrally 50 in the root, but sometimes owing to particular conditions it is advisable to set the tooth forward or backward on the root. For this

purpose I provide securing devices in which the pin 5 is secured at one side or the other of the center of the cross piece 4, the pin 55 5 being set to the rear of the center of piece 4 if the tooth is to be thrown forward, as in Fig. 1, and the pin 5 being set forward of the center if the tooth is to be situated farther back, the latter construction of device 60 being shown in Fig. 2. In many cases, however, the tooth will be centrally situated on the root, in which case the pin 5 will be at the middle of the cross piece 4, as shown in Fig. 4. The base of the tooth is formed 65 with a depression 40 to receive the cross piece 4.

Owing to the shape of some artificial front teeth it is sometimes desirable to make the rear holes 2 and pins 3 of less length than 70 the front holes and pins, this being shown in Figs. 1, 2 and 4. The invention is not limited to this feature, and in Fig. 5 holes 2^a and pins 3^a front and rear are of equal length. In this construction also the pins 75 are connected together by an angular plate 7 which fits on the horizontal shoulder of the tooth and upward along the back of the projection 8 of the tooth which extends over the edge of the saddle 9 and the natural 80 gum 10, and is secured by cement, rubber or the like, at 11.

The improvement may also be applied to molar or to back teeth 1' in Fig. 6, 2' being 85 holes for pins in a plane through the front and back of the tooth, and 41 a depression in the base of the artificial tooth to receive a pin-connecting cross-bar, as above described. The cross bar fitting into the depression 90 leaves the base of the tooth flat and smooth, and the wall of such depression incloses and hides the metal.

In use the main need for strong holding means for teeth is in a direction forward and backward, rather than sidewise, and my 95 construction provides this. Small pins may be used owing to their relative position without weakening the holding of the tooth, as compared with constructions in which the holes and pins are in a plane passing 100 through the edges of the tooth.

Having thus described the invention what I desire to secure by Letters Patent of the United States is;—

An artificial tooth having in its base end a plurality of pin-receiving holes, pins for said holes, a horizontal part connecting said pins, there being a depression in the base of the tooth to receive said horizontal part, and a root-pin secured to said horizontal part between the pins.

In testimony whereof, I have signed this specification in the presence of two subscribing witnesses.

MELVIN EDGAR MERKER.
